COMBINATION TOOL FOR USE BY WILD ANIMAL TRAPPERS

Stephen J. Zappa, Dwight, Ill.

Application June 24, 1955, Serial No. 36,684

Term of patent 14 years

(Cl. D35—2)

Figure 1 is a perspective view of the combination tool for use by wild animal trappers, showing my new design;

Figure 2 is a side elevational view looking to the left in Figure 1; and

Figure 3 is a top plan view of Figure 2.

The broken line showing of a handle is for illustration purposes only.

I claim:

The ornamental design for a combination tool for use by wild animal trappers, as shown and described.
